 Bendix Aviation Corporation, South Bend,
 Ind., a corporation of Delaware

Application July 26, 1940, Serial No. 347,633

6 Claims. (Cl. 261—76)

This invention relates generally to carburetors and particularly to fuel discharge jets for multiple Venturi carburetors.

In carburetor construction utilizing an inclined tubular type of main fuel nozzle from which the fuel is discharged angularly into the primary Venturi, it is found that the resulting fuel distribution in the induction passage is not uniform. At low engine speeds fuel is discharged from the nozzle with little force so that it tends to follow the nozzle side of the induction passage. The fuel mixture therefore tends to be richer along this side of the passage than along the other, resulting in non-symmetrical fuel delivery to the intake manifold and uneven distribution by the latter to the engine cylinders so that some cylinders receive a richer mixture than others. Such uneven distribution to the cylinders results in increased fuel consumption and decreased power, as is generally known, and may in extreme cases cause the engine to run unevenly.

On the other hand, during relatively high engine speeds, the fuel is drawn from the nozzle with considerable force and tends to flow along the side of the passage opposite the nozzle. Under these circumstances uneven distribution of the fuel mixture to the engine also occurs and irregular engine operation results.

It is an important object of the present invention to provide a multiple Venturi carburetor in which the fuel is uniformly distributed across the carburetor induction passage at all engine speeds.

Another object of the invention is to provide a device of this character that has a fuel discharge passage extending longitudinally of the carburetor induction passage, the fuel passage being flared outwardly at its discharge end.

Still another object of the invention is to provide a device of this character wherein fuel is discharged in the direction of air movement in the induction passage.

The invention is further characterized by elongation of the fuel discharge opening extending diametrically in the induction passage; and the extension of the opening entirely across the air passage at the plate of fuel discharge.

Other objects and advantages of the invention will appear from the following detailed description taken in connection with the accompanying drawing, in which:

Figure 1 is a vertical section through a carburetor embodying the invention;

Figure 2 is a bottom plan view of the small ven-

turi embodying the invention and taken on line 2—2 of Figure 1;

Figure 3 is a partial horizontal section taken on line 3—3 of Figure 1; and

Figure 4 is a partial vertical section taken on line 4—4 of Figure 1.

Referring more particularly to the drawing, there is shown, for the purpose of illustrating one embodiment of the invention, a downdraft carburetor having an air horn section 10, a main body section 12, and a throttle body section 14 having a flange 16 for attaching the carburetor to the intake manifold of the engine. The carburetor induction passage comprises an air inlet 18 controlled by an offset choke valve 20 mounted on a shaft 22 and controlled by any suitable manual or automatic means, a primary venturi 24, a secondary venturi 26, a mixing chamber 28, and a mixture outlet 30. A throttle valve 32 mounted on throttle shaft 34 controls the mixture outlet in the known manner.

A fuel chamber 36 in the main body section has a float 38 mounted by any well known means (not shown) for controlling the level L—L of fuel in the chamber. Idling jet 40 of known construction is supplied with idling fuel from chamber 36 by means of communicating passages 42, 44 and 46, the latter having the usual idling tube 48 secured therein. The lower end of passage 46 communicates with an acceleration well 50 formed by an enlargement of the bore in which main fuel jet 52, of known construction, is received. The jet 52 is secured in the bore by a plug 54 screwed into a boss formed integral with a wall of the main body section 12. The plug 54 is provided with a metering orifice 56 supplied with fuel from chamber 36 through passage 58 and air is bled into the jet 52 from an air bleed 60, in the known manner.

The main fuel discharge nozzle 62 is of the bar type and is formed integral with the small or primary venturi 24 in the entrance portion thereof, the small venturi being supported in the induction passage by diametrically extending integral webs 64. The nozzle 62 has a downwardly opening fuel discharge passage 66 gradually flaring convexly outwardly toward the discharge opening 68, the latter being at the downstream end of the nozzle so that fuel is discharged in the direction of movement of the air current. The opening 68 is elongated transversely of the nozzle and extends entirely across the Venturi tube at the place of discharge. The upper end of the passage 66 receives fuel from the main fuel jet 52 through a duct 70.

In operation, the nozzle 62 directs and discharges fuel in the same direction as the air stream, through the venturi in which said nozzle is disposed. The fuel discharge passage extends axially in the primary venturi thereby directing fuel in a uniform manner relative to the cross-sectional area of the venturi. By flaring the discharge end of the passage diametrically to the side walls of the venturi, a uniform discharge of fuel is provided diametrically across the full width of the venturi at the place of discharge, and one side of the induction passage receives substantially the same amount of fuel as the other regardless of engine speed.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof. Thus, the invention may be applied, not only to the double Venturi type of carburetor shown in the drawing, but also to triple or other multiple venturis, either of the updraft or downdraft type.

I claim:

1. In a carburetor, an induction passage including a large and a small venturi, and a relatively narrow bar nozzle integral with the small venturi and extending transversely within same, said nozzle having a fuel passage including a tubular portion coaxial with said small venturi and a narrow convexly flared portion terminating in an elongated discharge slot for discharging fuel in the direction of air flow in the induction passage.

2. In a carburetor having an induction passage, a bar nozzle in said induction passage having a fuel discharge duct for discharging fuel into said induction passage, said duct including a tubular portion and a slotted discharge opening substan-

ti ally rectangular in outline, said tubular portion gradually flaring outwardly to the ends of the discharge opening, and said flared portion being relatively narrow in width.

3. In a carburetor having an induction passage, a bar nozzle in said passage having a fuel discharge passage, said fuel discharge passage terminating at one end in an opening substantially rectangular in outline from which fuel is discharged into the induction passage, said fuel discharge passage being relatively narrow and curving convexly inwardly of the ends of said opening to an inlet portion.

4. In a downdraft carburetor having an induction passage, a large and a small venturi included in said induction passage, a narrow bar nozzle in the small venturi and integral therewith, said nozzle being substantially rectangular in cross section and having a convexly flared fuel discharge passage, the fuel discharge passage having a slot-like opening discharging down stream relative to the air current through the small venturi.

5. In a downdraft carburetor, an induction passage having a plurality of venturis therein, a downwardly discharging bar nozzle in one of said venturis, said nozzle having a narrow outwardly flared fuel passage terminating in a discharge opening extending across the venturi in which the nozzle is located, and means for bleeding air 30 to said fuel passage anterior to the discharge opening.

6. In a downdraft carburetor, an induction passage, and a relatively narrow bar nozzle therein having a fuel discharge passage including a tubular portion extending longitudinally of the induction passage and a narrow portion gradually flaring from the lower end of said tubular portion to a discharge opening substantially rectangular in outline and of substantially the same width as the diameter of the tubular portion, said discharge opening extending diametrically of the induction passage.
